UNITED STATES PATENT OFFICE.

WILLIAM S. COLWELL, OF CHICAGO, ILLINOIS.

APPARATUS FOR CONDENSING OR COOLING FLUIDS.

SPECIFICATION forming part of Letters Patent No. 716,383, dated December 23, 1902.

Application filed January 30, 1902. Serial No. 91,904. (No model.)

To all whom it may concern:

Be it known that I, WILLIAM S. COLWELL, a citizen of the United States, residing at Chicago, in the county of Cook and State of Illinois, have invented a certain new and useful Improvement in Apparatus for Condensing or Cooling Fluids, of which the following is a specification.

My invention relates to an apparatus for condensing steam and other vaporous fluids and for cooling fluids or liquids. With reference, for example, to the condensation of steam in an apparatus characterized by the principles and several features of my invention the steam is taken from any suitable source of supply and conducted to a condensing-chamber, wherein it is condensed. The steam thus obtained from the source of supply is cooled in an expanded condition within the condensing-chamber. As a means for cooling or reducing the temperature of the expanded condensing steam the condensing-chamber is provided with confining devices, such as a tube or pipe system, adapted to conduct currents of relatively cool air saturated with a cooling liquid through the condensing-chamber and to so confine these currents of air thus saturated with a cooling liquid as to prevent the same from being discharged into the body of expanded condensing steam. Means are also provided whereby the currents of air thus saturated with a cooling liquid shall be caused or induced to move rapidly through this cooling-pipe system, and hence rapidly and effectively absorb heat from the steam within the condensing-chamber.

As a matter of further improvement the cooling system comprises a series of pipes extending through the condensing-chamber and arranged to receive at one end of the set a supply of external air which is relatively cooler than the steam, the rapid passage of the air through the pipes being secured by an exhaust-fan at the opposite end of the set, and in order to saturate the relatively cool air-currents with a relatively cool liquid, so as to further reduce the temperature of the air-currents, a liquid-spraying device is arranged in opposition to the series or collection of receiving ends of the pipes and adapted to spray the liquid into the inflowing currents of air. The saturated air which thus passes

through the pipes becomes heated to the extent to which it absorbs heat from the condensing steam within the condensing-chamber and issues from the pipes as heated vapor. When so desired, the vapor can be condensed and the water of condensation therefrom can be collected and automatically taken up by steam from the source of supply to the condenser. On the other hand, all or a portion of the heated vapor which issues from the cooling system can be conducted to any desired point or points and utilized for heating purposes. In order to increase the general efficiency of the apparatus, the steam on its way from the source of supply to the condensing-chamber is admitted into a distributing-chamber. The steam expands to some extent within this distributing-chamber, and the latter is provided with means whereby the flow of steam through such chamber can be retarded or accelerated at will, so as to vary the pressure in accordance with requirements and conditions, and as a matter of further improvement the steam passing through the distributing-chamber can be variably deflected toward different points of outlet with which the distributing-chamber is provided. In order to more effectively expand the steam and permit it to circulate about and around the cooling-tubes in an expanded condition, an expanding-chamber is arranged between the distributing and condensing chambers, and as a simple, compact, and highly efficient arrangement the cooling-pipe system can be arranged within the lower portion of the condensing-chamber, whereby a portion of such chamber above the cooling-pipe system can be utilized as an expanding-chamber. The water of condensation can be drawn off from the condensing-chamber and used while in a heated condition, or it can be conducted from the condensing-chamber to and through a cooling device, wherein it can be rapidly and economically cooled by the agents employed for reducing the temperature of the condensing steam within the condensing-chamber. Exhaust-steam can also be admitted to the condenser, and when thus used the exhaust-steam is caused to pass through an oil-separator, which serves to free the exhaust from oil and other foreign matters. The distributing-chamber and its adjuncts also serve to free

the main steam-supply from lime and other foreign matters, and means are also provided whereby any scum or the like floating upon the water of condensation within the 5 condensing-chamber will not pass out therefrom with the outflow of water.

Objects of my invention are to secure an effective distribution of steam within the condensing-chamber containing a cooling system, 10 to accelerate and retard the flow and distribution of the steam in accordance with requirements or conditions, to vary the expansion of the steam on its way to the condensing-chamber, to provide for the cooling-pipe 15 system a minimum supply of spray-water having a maximum efficiency, to avoid waste of the spray-water, to secure a highly effective expansion of the steam passing into the condensing-chamber, to supply the cooling 20 system with currents of vapor formed by saturating currents of relative cool air with relatively cool liquid, to subsequently reclaim the liquid thus employed, and where water is thus employed and the apparatus is used for 25 condensing steam to permit the water thus reclaimed to be taken up by the main supply of steam passing from a suitable source of supply to the condenser, to utilize the heated vapor from a cooling-pipe system for other 30 and various purposes when so desired, to use the water of condensation while in a heated condition or to divert the water of condensation from its normal outgoing passage and rapidly and effectively cool it by means em- 35 ployed for forming currents of saturated air within the main cooling system, to utilize exhaust-steam and to free it from oil and other impurities while on its way to the condenser, to also free the main supply of steam from 40 lime or other foreign matters, to permit the water of condensation to be drawn off from the condensing-chamber in a pure condition, to avoid waste of heat, to provide a construction of apparatus which can be readily taken 45 apart and cleaned, to provide compact and highly efficient construction of apparatus, to provide a distributing chamber or passage having an adjustable or variable capacity for the flow and distribution of steam, to adapt 50 the apparatus whereby it can be adjusted for condensing steam or other vapors or for cooling fluids or liquids, and to provide certain novel and improved matters of construction, detail, combination, and arrangement, sub- 55 stantially as hereinafter set forth.

In the accompanying drawings, Figure 1 represents in side elevation a construction of condensing apparatus embodying the principles of my invention. Fig. 2 is a longitudinal section taken on a vertical central plane through said apparatus with the exhaust-fan and pipe or stack therefrom omitted. Fig. 3 is a transverse section through the upper portion of the apparatus on line 3 3 in Fig. 2. 60 Fig. 4 represents a portion of the main steam-supply pipe E, partly in longitudinal section and partly in elevation, and also shows in lon-

gitudinal section a vaporizing-chamber arranged around a portion of said steam-supply pipe. Fig. 5 is an end elevation of the apparatus with the spray device removed and showing the oil-separator R in section on line 5 5 in Fig. 2. Fig. 6 is a section on a horizontal plane through a device for cooling the water of condensation. Fig. 7 is a detail showing in end elevation and on a larger scale than in Fig. 5 a portion of the series of flared receiving ends of the tubes or pipes for the cooling pipe or tube system. Fig. 8 is a detail showing, partly in section and partly in elevation, a hollow guard which is arranged relatively to the outlet for the condensing-chamber to prevent floating scum from passing through such outlet, a portion of one wall of said hollow guard or shield being broken 85 away for convenience of illustration. Fig. 9 represents in perspective one of the hollow cones of the oil-separator R. Fig. 10 is a perspective view of one of the end portions of the cooling-tubes. Fig. 11 is a longitudinal 90 section, on a vertical central plane, through the main casing and illustrates another form of valved distributing-chamber. Fig. 12 shows an apertured slide adapted to form a valve or cut-off for the upper apertured portion of the distributing-chamber. Fig. 13 shows an apertured slide adapted to form a valve or cut-off for the apertured base or bottom of the distributing-chamber. Fig. 14 is a section through the distributing-chamber 100 on line x x in Fig. 11.

Referring to the first ten figures of the drawings, the shell or casing A contains a series of communicating chambers which progressively constitute a distributing-chamber B, an expanding-chamber C, and a condensing-chamber D. The steam or fluid supply pipe E, Figs. 1 and 4, can be connected with a suitable boiler or generator and is suitably extended to provide a steam or fluid conducting passage which connects with one end of the distributing-chamber B. The expanding-chamber C is arranged between the distributing-chamber and the condensing-chamber, and the latter is provided with a series 115 of pipes 11, which extend through the condensing-chamber and open externally thereto, whereby the cooling agent or agents employed may pass through and cool the pipes, and thereby secure rapid condensation with- 120 in the condensing-chamber. A spraying device F, which is understood to be connected with some suitable source of water-supply, is arranged opposite the inlet ends of the cooling-pipes 11, Fig. 2, and the opposite outlet 125 ends of such pipes are arranged to discharge into a hood or chamber G, which connects with an exhaust-fan H. By this arrangement relatively cool air-currents induced through the cooling-tubes will take up and carry the 130 relatively cool liquid which is primarily directed by the spraying device toward the inlet ends of the tubes. The water which is thus taken up by the air and carried through

and discharged from the tubes in the form of vapor can be reclaimed and taken up by the steam-supply passing to the condensing portion of the apparatus when steam is used, 5 and to such end I provide a drip-trap I, which serves to collect the reclaimed water and from which the water is taken by the passing steam-supply in regulated quantities.

With reference to the construction illustrated, the steam-supply pipe E is provided with a steam-throttle valve 12 for establishing and cutting off the flow of steam and with a weighted or other automatic regulating-valve 13 for controlling the supply of 15 steam to the condenser and insuring a uniform flow and pressure in accordance with the work required. At a point between the valves 12 and 13 the main steam-supply pipe or passage connects with a similar branch pipe 20 20 14, forming a lateral passage, which is provided with an ejector 15 for taking up the drip-water, and in order to insure a proper supply of drip-water to the ejector the latter is provided with a cock 16, which is automatically 25 operated by a float 17, arranged within the drip-trap. The branch pipe or passage 14 connects with and takes steam from the main supply pipe or passage, so as to supply the ejector, and thereby take up the drip-water and dis- 30 30 charge into a vaporizing-chamber K, where the drip-water is vaporized. This vaporizing-chamber K is preferably formed around a portion of the main steam-supply pipe or passage and is extended, as at 18, Fig. 4, so as to sur- 35 35 round a perforated portion 19 of the main steam-supply pipe or passage, in which way the vapor from chamber K, which surrounds a portion of the heated main steam-supply pipe or passage, will enter the latter and there 40 40 mingle with the passing steam-supply.

The chamber of the hood G, into which vapor from the cooling-pipes is discharged, is provided with a drip-pipe 20 for conducting from the hood-chamber to the drip-trap 45 such water as may collect within the hood-chamber. The exhaust-fan chamber also connects by suitable pipe or passage 21 with an exhaust-head L, comprising a suitable drum or casing containing a rotary spiral 50 50 partition 22, Fig. 5, arranged to form a spiral passage in continuation of the exhaust-passage through the pipe 21. By such arrangement the vapor passing through the exhaust head or collector L will condense upon the 55 spiral partition, from which latter the water can pass through lateral openings in the exhaust-head to and through corresponding openings in a drip-pipe M, which is arranged to discharge into the drip-trap. The residue 60 60 of heated vapor passing out from the exhaust-head can be discharged into the open air, or it can be diverted through any suitable arrangement of branch pipe or pipes and employed for heating purposes. As illustrated, the exhaust-head connects with lateral branches 23 24, having a valve 25 arranged at their point of junction, whereby the heated

vapor can be caused to pass through either branch.

The distributing-chamber B is provided with perforated wall portions and is relatively of less transverse superficial area than the transverse area of the upper interior portion of the casing A, thereby permitting the distributing-chamber to discharge into a 70 space or chamber portion which merges into the expanding-chamber C. In the arrangement shown the distributing-chamber is, in effect, located within the upper portion of the chamber C, which said chamber has its upper portion contracted by reason of the presence of the distributing-chamber. As a preferred construction the distributing-chamber is formed by an oblong transversely-segmental shell or casing having a bottom 26 and a 75 perforated arch-shaped upper portion 27, as in Fig. 3, in which the bottom wall 26 of the chamber is imperforate. With such arrangement the top portion of casing A may correspond in form with the upper arch-shaped 80 portion of the distributing-chamber, so as to leave between the two a transversely-segmental space or passage which merges downwardly into the expanding-chamber C. The form of this distributing-chamber may, how- 85 85 ever, be varied without departing from the spirit of my invention.

The distributing-chamber B is provided with means for retarding or accelerating the flow of steam and for varying the distribution 100 thereof in accordance with requirements. As an effective arrangement the distributing-chamber contains a series of adjustable deflectors consisting of vibratory perforated segment-plates 28, which are alternately hinged 105 within upper and lower portions of the distributing-chamber. These perforated deflectors can be set at any desired angle for the purpose of varying the flow of steam, and to such end they can be adjusted by a longitudinally-movable controlling-rod 29, arranged 110 to extend through slots 30 in the deflecting-plates and provided with stops or pins 31 at opposite sides of such plates. The rod 29 is shown extending through a pipe-section 32 115 (which is a continuation of the main steam-supply pipe) and passing out through a stuffing-box 33. The rod thus arranged is operated by a lever 34, supported upon the main casing, and this lever can be locked in desired 120 position by any suitable latch device—for example, by a pin 35 and a perforated segment 36 on the main casing. The distributing-chamber has an imperforate end wall 37 (with the exception of an opening to which the supply-pipe section 32 is fitted) and is removable 125 from the casing A, so that it can be taken out and freed from lime and other deposits which may collect upon the deflecting-plates and its inner wall. To such end, therefore, the main 130 casing is provided with internally-arranged bars 38, which support the removable distributing-chamber and upon which the latter can slide. With such arrangement the

end wall 39 of the main casing will have a suitable opening for the insertion and removal of the distributing-chamber.

The expanding-chamber C may simply comprise the portion of the space within the main or condenser casing which is intermediate of the upper and lower portions, respectively, occupied by the distributing-chamber and the cooling-tubes, in which way a compact arrangement is secured. In order to insure the passage of steam between the tubes in place of between the collective body of tubes and the inner wall of the main or condenser casing A, deflectors 40 are arranged within the latter and conveniently formed by angle-irons bolted to the inner longitudinal sides of the casing. The receiving ends of the cooling-tubes are outwardly flared or provided with tube-sections 41, which are fitted within the tubes and formed with outwardly-flaring mouths 42, which receive the spray. The outer terminal portions of these flaring mouths or ends for the cooling-tubes are formed to fit closely together in groups or series, as illustrated in Fig. 5. With such arrangement there will be no gaps or spaces between the juxtaposed outer terminal portions of the flaring mouths 42, and hence the tubes, which are separated to permit the circulation of steam between and around their portions within the condenser, will present to the spray a collection of expanded receiving ends arranged without intervening spaces. In this way the spray will be collected by the tubes without waste, and hence a minimum quantity of spray-water can be used. In order to increase the efficiency of these expanded end portions of the tubes, their lower sides 43 are desirably arranged in planes parallel or substantially parallel with the longitudinally-extending passages through the tubes, so that spray-water which falls upon these lower sides 43 of the expanded tube ends will be readily carried into the tubes by the inflowing currents of air.

The condensing-chamber is connected with a pipe N for the outflow of the water of condensation. In order to prevent any scum or floating matters from flowing out of the condenser with the water of condensation, the entrance to such discharge pipe or passage is arranged to open into a shield O, Fig. 8, adapted to form a chamber which is closed at its sides and top and formed with an open bottom which is positioned near the bottom of the condensing-chamber, so as to leave between the two a passage which will be below the surface of a body of water within the condensing-chamber. The outer pipe N is provided with a cock or valve 44, Fig. 1, whereby it can be opened and closed, and at a point between the valve 44 and the receiving end of said pipe N, I connect with the latter a branch pipe P, which extends upwardly from the pipe N and then laterally, so as to connect with a cooling device Q, Figs. 2 and 6, whereby the water of condensation can be further cooled

by the cooling device or apparatus and then discharged from the latter by an outlet-pipe 45. The cooling device Q comprises a chamber which is arranged below the set of cooling-tubes and provided with a tortuous passage for the flow of water. The walls of the chamber of this cooling device are subjected to the cooling vapor formed by the conjunction of spray from the spray device and currents of air introduced by the exhaust-fan, and to such end the cooling device Q may consist of a flat, shallow, closed casing 46, containing a series of longitudinally-arranged partitions 47, which alternately terminate short of opposite end portions of the casing, so as to form tortuous passage 48, connecting at one end with an inlet-pipe P and connecting at its opposite end with an outlet-pipe 45. The cooling device, which is, in effect, a flat coil of pipe or a pipe bent to form a series of reverse bends, is arranged within a space formed between the bottom 49 of the condenser-casing A and a partition 50, which is arranged to form a bottom for the condensing-chamber D, which said space is of sufficient depth to leave longitudinal passages 51 respectively above and below the cooling device. These passages open at their ends through opposite sides of the casing A, the ends of said passages at one end of the casing being arranged to receive spray from the spraying device and to take in air and their opposite ends being arranged to open into the hood G. By this arrangement the valve 44 can be closed, and the water of condensation from the condensing-chamber will thereupon flow through the trap formed by the pipes N and P and thence into and through the cooling device, in which latter the water will be cooled, so as to render it serviceable for uses requiring water of a temperature lower than the water normally passing out through the discharge-pipe N.

The condensing-chamber can be provided at opposite sides with hand-holes which normally close by hand-hole plates, one of such plates 52 being illustrated in Fig. 1. Exhaust-steam from the generator for engine may also be admitted to the condenser, and thereby utilized, and in order to free the exhaust-steam from impurities preparatory to its admission into the condenser the apparatus is provided with an oil-separator R, comprising a nest or series of hollow cones 53, arranged one within another and held apart by suitable connections, so as to leave spaces or passages between them. The cones 53 are arranged within a casing 54, having an open end which is secured opposite one end of the distributing-chamber B and having its opposite end 55 connected with a valved supply-pipe S and arranged to leave space or passage between said end portion and the outermost hollow cone. These hollow cones 53 are each provided with an opening 56, which said openings are alternately at opposite sides of the series of hollow cones, so as to insure circulation of the exhaust through the passages

formed by these hollow cones. With such arrangement the end wall 57 of the distributing-chamber B is perforated, so as to permit such chamber to receive the exhaust from the oil-separator. The oil-separator is also provided with a lower drip-trap or oil-receiver 58, into which oil collecting upon the surfaces of the hollow cones may pass through openings 59 in the lower portion of the shell or casing 54. The trap or receiver 58 is also provided with a valved outlet-pipe T, through which the oil may be discharged. The conical end portion 55 of the casing which contains the hollow cones is detachably bolted or secured to the remaining portion of the casing, as at 60, and the hollow cones are bolted together in any suitable way, as at 61, whereby the said casing can be opened and the hollow cones removed, separated, and cleaned.

In using an apparatus as hereinbefore described steam from the boiler is taken by pipe E, having a regulating-valve 13, whereby the flow and pressure of steam is regulated. A portion of the steam thus admitted to and passing along the main supply-pipe E passes through the ejector 15, where it takes up water from the drip-trap I and thence passes along the vaporizing-chamber K to the point it enters the main steam supply or passage through the perforated portion 19 of said pipe, the steam from the vaporizing-chamber K entering the main supply pipe or passage at said point and mingling with the passing main supply of steam which is conducted to the distributing-chamber B of the condenser. The steam which enters the distributing-chamber expands proportionally to the area of such chamber, the number and size of the perforations which form its outlets, and the adjustment of the deflectors 28. The steam coming into contact with these perforated deflectors passes through and around and is distributed evenly throughout the distributing-chamber and deposits lime or other foreign substances both on the deflecting-plates and on the bottom of the distributing-chamber. The adjustment of these deflecting-plates also serves to check or accelerate the flow of steam into the condenser, as may be desired—as, for example, when it is desired to admit steam into the condenser at a greater pressure the deflecting-plates may be tilted toward an upright position by drawing the rod 29 outwardly, and when it is desired to admit steam into the condenser at a lower pressure the deflecting-plates can be tilted toward a longitudinal position by pushing the rod 29 inwardly, it being understood that the pressure will increase proportionally to the increase of obstruction presented in opposition to its flow and that by lessening the obstruction presented the pressure will be lowered. In this way an even distribution of steam can be secured throughout the distributing-chamber, and hence an even distribution of steam can be secured throughout the condenser, it being observed that the more even the distribu-

tion of steam the better are the results attained. It will be seen, therefore, that the deflecting-plates can be adjusted so as to provide the passage-way within the distributing-chamber with transverse partitions separating such passage-way into compartments which communicate one with another only through the perforations in the deflecting-plates, and also that these deflecting-plates can be adjusted so as to leave spaces between their edges and the inner wall of the distributing-chamber, also that these spaces between the edge portions of the deflecting-plates and the inner wall of the distributing-chamber can be varied in area by suitably adjusting the deflecting-plates, and that they thereby form variable openings between the portions of the distributing-chamber which are intermediate of the deflecting-plates. The distributing-chamber extends over the condensing-chamber, as well as over the intervening expansion-chamber C, and has its side and top wall portions provided with perforations or apertures, which are distributed along the length of the distributing-chamber, and in this way steam will be distributed over the entire cooling-pipe system. The distributing-chamber therefore provides a passage along which the steam is conducted and from which the steam is distributed at different points along its length. This passage-way, which is thus formed by the distributing-chamber, is, in effect, provided with a valve system formed by the adjustable deflectors and adapted for varying the area of such passage-way or passage, it being manifest that these deflecting-plates may subdivide the said passage-way and that they can be adjusted to vary the area of ports or openings between the portions of the passage-way intermediate of such deflecting-plates. The steam from the distributing-chamber passes into and is further expanded within the expanding-chamber C, and by reason of the pressure above and a less pressure below the steam is caused to pass downwardly between and around the tubes 11 until it is condensed. The rapidly-flowing vapor within these tubes absorbs the heat given up by the condensing steam, and this heat may by a suitable arrangement of pipes be transmitted to the boiler-furnace or utilized for heating purposes, or it may simply pass out into the open air, as may be desired. The water of condensation which flows out from the pipe N may be allowed to pass the valve 44 and used as desired—as, for example, for feed-water for boilers or for any other purpose where high temperature is needed. The water of condensation may, however, be caused to pass through the cooling device Q by closing the valve 44, in which way the water will be cooled, so that it can be used for domestic or other purposes involving the desideratum of cooler water. The exhaust-steam from an engine-pump or other steam-using device can be permitted to pass through the oil-separator R, where it will be

freed from oil or other foreign substances, and from such oil-separator the exhaust will pass into the distributing-chamber, where it will follow the course hereinbefore described in connection with the supply of live steam.

It will be apparent that during the operation of the foregoing-described condenser the water of condensation may be taken at two or more different temperatures—for example, one comparatively hot, if desired for feed-water for the boilers, and another comparatively cool for domestic purposes—and that when desired the cooling device hereinbefore described can be duplicated or multiplied and connected in series, so as to still further reduce the temperature of the water. It will also be seen that the volume of the water of condensation will be largely augmented or increased by the drip-water vaporizing with the steam and that the drip-water will not be wasted, as heretofore; also, that by arranging the receiving ends of the cooling-tubes as hereinbefore described a minimum amount of spray-water can be used, since there will practically be no waste.

In the last four figures of the drawings the deflectors are omitted from the distributing-chamber B; but it is understood that they may be used therein, if so desired. The reflecting-chamber B in these figures has an apertured upper portion 27, as in preceding figures, and in addition thereto its base or bottom 26 in place of being imperforate, as in Figs. 2 and 3, is perforated or apertured at various points, it being understood that these perforations through the wall or walls of the chamber may be of any desired form, such as, for example, circular or oblong holes or slots. The retardation and acceleration of the flow of steam or other vapor through the portion 27 of the distributing-chamber (shown in Fig. 11) can be controlled by a valve 62, comprising a transversely-curved, perforated, or apertured plate formed to fit against and slide along the upper apertured portion 27 of the chamber B and having perforations or apertures corresponding with the apertures of said upper portion of the distributing-chamber. The valve 62 can be adjusted longitudinally in any suitable way—as, for example, by a lever 63, attached to a rod 64, which is in turn secured to the valve and operating in the way in which the lever for actuating the deflecting-plates in Fig. 2 operates. The plate 62 may be within or outside of the deflecting-chamber, it being preferably arranged therein as illustrated.

The perforated or apertured valve 65 of Figs. 11, 12, and 14 is arranged to slide along the perforated or apertured bottom 26 of the distributing-chamber, and while it may be arranged under the bottom of such chamber it is preferably arranged within the chamber, as shown. The perforations of the plate 65 which forms the valve 65 also correspond with the perforations or apertures through the bottom 26 of the distributing-chamber.

Valves 65 can be adjusted by a lever 66, attached to a rod 67, which is in turn secured to the valve, whereby the latter can be shifted along the bottom of the distributing-chamber.

Where steam or other vapor under pressure is admitted to the distributing-chamber B, the bottom of such chamber is preferably closed by adjusting valve 65 in a direction to bring its openings out of register with the openings through the bottom of the distributing-chamber, and by adjusting the valve 62 the openings through the upper portion 27 of the distributing-chamber can be varied in area in accordance with the extent to which they are covered or uncovered by the perforated or apertured valve 62. In this way steam or other vapor under pressure can be permitted to expand within the distributing-chamber to a degree determined by the adjustment of valve 62, and while the steam or other vapor can be permitted to pass out from the distributing-chamber at different points of outlet the flow of such steam or other vapor through the distributing-chamber and its flow from such chamber can be retarded or accelerated by adjusting valve 62 in accordance with requirements. Where a liquid is to be passed through the apparatus and cooled, the valve 65 can be adjusted so as to bring its openings into register with the openings through the bottom of the distributing-chamber, and the openings through the remaining portion of such chamber can be opened or closed, as desired.

In Fig. 11 the spray device is shown arranged as in certain preceding figures, and in this, as in said other figures, the end wall of the casing A may be provided with a hood or guard 68, arranged around the set of mouths or inlets for the pipes 11 and the passage 51 above and below the cooling device Q.

From the foregoing-described matters it will be seen that the distributing-chamber is provided with outlets at different points, whereby a distribution of a fluid in either vaporous or liquid form over the series of cooling-pipes may be insured, and that the valves or deflecting-plates 28, as well as the valve 62, serve to provide the distributing-chamber with means or a valve device or arrangement whereby the flow of steam or other vaporous fluid under pressure through the distributing-chamber can be regulated and either retarded or accelerated at will and in accordance with need; also, that the deflector-plates 28 of the valve device 62, used either separately or together, will also serve to regulate the flow of other fluid, such as a liquid under pressure, but that where the fluid is in liquid form the bottom of the distributing-chamber is preferably perforated and a perforated valve employed in connection therewith. It will also be seen that the spray device may be connected with any suitable source of supply of liquid under suitable pressure and at a suitably-reduced temperature and that the spray ejected from the spray-

ing device can commingle with air at atmospheric temperature (or, if desired, at a previously-reduced temperature) at the points where the air is drawn into the passageways of a 5 cooling system, which to insure highly-effective and quick results is composed of a set or multiplicity of pipes or tubes. The air-currents therefore practically pass through a spray of liquid at the points where they enter 10 the tubes and are thereby further cooled preparatory to passing through the tubes, which are in a heated condition.

What I claim as my invention is—

1. In an apparatus for condensing vaporous 15 fluid, a distributing-chamber having outlets at different points; suitable means for supplying the distributing-chamber with vaporous fluid; and a condensing-chamber wherein vaporous fluid distributed by the distributing-chamber is received and condensed, the outlets of the distributing-chamber being arranged to disseminate the vaporous fluid over the area of the condensing-chamber.

2. In an apparatus for condensing vaporous 25 fluids, a condensing-chamber; a distributing-chamber arranged over the condensing-chamber and communicating therewith by perforations or apertures formed through its walls at different points, said apertures being arranged to disseminate the vaporous fluid over the area of the condensing-chamber; and suitable means for supplying the distributing-chamber with vaporous fluid.

3. In an apparatus for condensing vaporous 35 fluids; a condensing-chamber; an oblong, transversely-segmental distributing-chamber arranged over the condensing-chamber and communicating therewith by perforations or apertures formed at different points through its wall portions, whereby the vaporous fluid is disseminated over the area of the condensing-chamber; and suitable means for supplying the distributing-chamber with vaporous fluid.

4. In an apparatus for condensing vaporous 45 fluids, a condensing-chamber containing a cooling-pipe system and providing an area of space for the expansion of the vaporous fluid; a distributing-chamber provided at different 50 points with outlets arranged to disseminate the vaporous fluid within the expanding-space thus provided by the condensing-chamber; and suitable means for supplying vaporous fluid such as steam to the distributing-chamber.

5. In an apparatus for condensing vaporous 55 fluids, a distributing-chamber having outlets at different points; suitable means for supplying the distributing-chamber with vaporous fluid; an expanding-chamber into which the vaporous fluid from the distributing-chamber is disseminated; and a condensing-chamber wherein the expanded vaporous fluid from the expanding-chamber is received and 60 condensed.

6. In an apparatus for condensing vaporous 65 fluids, a condensing-chamber; a distributing-

chamber arranged over the condensing-chamber and having outlets formed at different points; and an expanding-chamber arranged 70 between and communicating with the distributing and condensing chambers; and suitable means for supplying vaporous fluid to the distributing-chamber.

7. In an apparatus for condensing vaporous 75 fluids, a condensing-chamber; an oblong, transversely-segmental distributing-chamber arranged over the condensing-chamber and provided with outlets formed at different points through the wall portions above its bottom; suitable means for supplying vaporous fluid to the distributing-chamber; and an expanding-chamber arranged between and communicating with the distributing and condensing chambers. 80

8. In an apparatus for condensing vaporous 85 fluids, a distributing-chamber adapted to permit an expansion therein of admitted vaporous fluid under pressure, and provided at different points with outlets; a condensing-chamber; and an expanding-chamber communicating with and arranged between the distributing and expanding chambers and adapted to permit the further expansion of vaporous fluid which it received from the distributing-chamber. 90

9. In an apparatus for condensing vaporous 95 fluids, a distributing-chamber provided with a pressure-regulating device for varying fluid-pressure therein; suitable means for supplying the distributing-chamber with vaporous fluid; and a condensing-chamber wherein vaporous fluid from the distributing-chamber is received and condensed. 100

10. In an apparatus for condensing vaporous 105 fluids, a distributing-chamber provided with an adjustable valve device for retarding and accelerating the flow of vaporous fluid through such chamber; suitable means for supplying vaporous fluid to the distributing-chamber; and a condensing-chamber wherein vaporous fluid from the distributing-chamber is received and condensed. 110

11. In an apparatus for condensing vaporous 115 fluids, a distributing-chamber having outlets at different points and provided with an adjustable valve device for retarding and accelerating the flow of vaporous fluid through such chamber; suitable means for supplying vaporous fluid to the distributing-chamber; and a condensing-chamber wherein vaporous fluid from the distributing-chamber is received and condensed. 120

12. In an apparatus for condensing vaporous 125 fluids, a condensing-chamber; a distributing-chamber arranged over the condensing-chamber, and having outlets formed at different points, and provided with an adjustable valve device for retarding and accelerating the flow of vaporous fluid through such 130 chamber; and suitable means for supplying vaporous fluid to the condensing-chamber.

13. In an apparatus for condensing vaporous 135 fluids, a condensing-chamber; an oblong,

- transversely-segmental distributing-chamber arranged over the condensing-chamber and communicating therewith by perforations or apertures formed at different points through its wall portions; suitable means for supplying vaporous fluid to the distributing-chamber; and an adjustable valve device applied for retarding and accelerating the flow of vaporous fluid through the distributing-chamber.
14. In an apparatus for condensing vaporous fluids, a distributing-chamber connected with vaporous-fluid-supply passage, and adapted to permit the expansion of the admitted vaporous fluid, and provided with an adjustable valve device for retarding the flow of vaporous fluid through such chamber; and a condensing-chamber wherein vaporous fluid from the distributing-chamber is received and condensed.
15. In an apparatus for condensing vaporous fluids, a distributing-chamber provided with outlets at different points; suitable means for supplying vaporous fluid to the distributing-chamber; a valve device applied for retarding and accelerating the flow of vaporous fluid through the distributing-chamber and comprising adjustable deflector-plates; and a condensing-chamber wherein vaporous fluid from the distributing-chamber is received and condensed.
16. In an apparatus for condensing vaporous fluids, a condensing-chamber; a distributing-chamber provided with outlets at different points and arranged over and communicating with the condensing-chamber; and a valve device arranged within the distributing-chamber and comprising one or more adjustable deflecting-plates.
17. In an apparatus for condensing vaporous fluids, a distributing-chamber having perforated wall portions; a set of adjustable, perforated deflector-plates arranged within the distributing-chamber and adapted for retarding and accelerating the flow of vaporous fluid through the distributing-chamber; suitable means for supplying vaporous fluid to the distributing-chamber; and a condensing-chamber wherein vaporous fluid from the distributing-chamber is received and condensed.
18. In an apparatus for condensing vaporous fluids, a distributing-chamber provided with perforated wall portions; suitable means for supplying vaporous fluid to the distributing-chamber; an adjustable, perforated valve device associated with the distributing-chamber for retarding and accelerating the flow of vaporous fluid through the same; and a condensing-chamber wherein vaporous fluid from the distributing-chamber is received and condensed.
19. In an apparatus for condensing vaporous fluids, a shell or casing; a condensing-chamber formed by the lower portion of space within the casing; a perforated shell or casing arranged within the upper portion of such space within the casing and forming a distrib-

uting-chamber which is relatively contracted to leave unoccupied space portions or passageway between its perforated wall portions and the casing by which it is inclosed; and suitable means for supplying vaporous fluid to the distributing-chamber.

20. In an apparatus for condensing vaporous fluids, a distributing-chamber having a perforated upper portion; suitable means for supplying vaporous fluid to the distributing-chamber; and a condensing-chamber arranged below and communicating with the distributing-chamber.

21. In an apparatus for condensing vaporous fluids, a main shell or casing; a condensing-chamber formed in the lower portion of such shell or casing; a distributing-chamber formed by a perforated shell or casing removable arranged within the upper portion of the main shell or casing; and suitable means for supplying vaporous fluid to the distributing-chamber.

22. In an apparatus for condensing vaporous fluids, a condensing-chamber; a distributing-chamber; having outlets at different points; and one or more tilting deflector-plates arranged within the distributing-chamber and connected with a longitudinally-movable adjusting-rod.

23. In an apparatus for condensing vaporous fluids, a distributing-chamber formed by an oblong, transversely segmental, perforated shell, connected at one end with a vaporous-fluid-supply passage; a series of perforated, segmental plates hinged within the distributing-chamber; an adjusting device for varying the angle of the hinged plates; and a condensing-chamber wherein vaporous fluid from the distributing-chamber is received and condensed.

24. In an apparatus for condensing or cooling fluids, a condensing or cooling chamber; a cooling-pipe system extending through the condensing or cooling chamber; an exhaust device for inducing a rapid flow of air through the cooling-pipe system; a spraying device for spraying liquid into the air passing within the cooling-pipe system; and a fluid-distributor provided with outlets at different points and arranged over the cooling-pipe system and organized to disseminate the fluid within the chamber containing the cooling-pipe system.

25. In an apparatus for condensing vaporous fluids, a perforated distributing-chamber connected with a suitable vaporous-fluid-supply passage; a condensing-chamber provided with a cooling-pipe system; means for inducing currents of air saturated with a cooling liquid through the cooling-pipe system; and an expanding-chamber arranged between and communicating with the distributing and condensing chambers.

26. In an apparatus for condensing vaporous fluids, a distributing-chamber provided with outlets at different points and connected with a suitable supply-passage; a condens-

- ing-chamber containing a cooling-pipe system and arranged for receiving vaporous fluid from the distributing-chamber; and a valve device for retarding and accelerating the flow 5 of vaporous fluid through the distributing-chamber.
27. In an apparatus for cooling or condensing fluids, a perforated distributing-chamber; suitable means for supplying the perforated 10 distributing-chamber with a fluid to be cooled or condensed; a cooling or condensing chamber wherein fluid from the distributing-chamber is received; a set of pipes extending through the cooling or condensing chamber; 15 means for inducing fluid currents through the pipes; and an adjustable valve device for varying the discharge of fluid from the distributing-chamber.
28. A cooling or condensing chamber provided with a cooling-pipe system; means for inducing a flow of cooling fluid through the cooling-pipe system; a distributing-chamber arranged over the condensing-chamber and having a perforated bottom or under side portion; and an adjustable perforated valve for varying the areas of the perforations through the bottom or under side portion of the distributing-chamber.
29. In an apparatus for condensing vaporous fluids, a condensing-chamber; a cooling-pipe system extending through the condensing-chamber; means for inducing cooling-currents of fluid through the cooling-pipe system; a distributing-chamber provided with 35 outlets at different points; and an expanding-chamber arranged and communicating with the distributing and condensing chambers.
30. In an apparatus for condensing vaporous fluids, a condensing-chamber; a cooling-pipe system extending through the condensing-chamber; means for inducing cooling-currents of fluid through the cooling-pipe system; a distributing-chamber provided with outlets at different points; an expanding-chamber arranged between and communicating with the distributing and condensing chambers; and a valve device for retarding and accelerating the flow of vaporous fluid through the distributing-chamber.
31. A cooling or condensing chamber; a set of pipes extending through the cooling or condensing chamber; an exhaust device for inducing currents of air through the pipes; a spraying device for directing liquid spray to the air entering the pipes; a distributing-chamber arranged over the set of pipes and comprising a perforated casing connected with a fluid-supply passage; and an adjustable valve device applied to the distributing-chamber as a means for varying the flow and discharge of fluid.
32. In an apparatus for condensing or cooling fluids, a set of pipes open at their ends and extending through the condensing or cooling chamber; means for inducing fluid currents through the pipes; and a spray device for directing spray to the receiving ends of the pipes which have their receiving ends expanded and grouped together to present to the spray a group of mouths without intervening spaces.
33. In an apparatus for condensing vaporous fluids, a condensing-chamber; suitable means for supplying vaporous fluid to the condensing-chamber; a cooling-pipe system 75 extending through the condensing-chamber; means for inducing currents of air saturated with liquid through the cooling-pipe system; and means for reclaiming and transferring such liquid to the supply of vaporous fluid 80 passing to the condensing-chamber.
34. In an apparatus for condensing vaporous fluids; a condensing-chamber; suitable means for supplying vaporous fluid to the condensing-chamber, a cooling-pipe system 85 extending through the condensing-chamber; means for inducing currents of air saturated with liquid through the cooling-pipe system; means for condensing the vapor which has passed out from the cooling-pipe system, and 90 for collecting the water of condensation; and an ejector supplied from the main supply of vaporous fluid passing to the condensing-chamber and operating to take up said water of condensation and cause the same to commingle with the main supply of vaporous fluid.
35. In an apparatus for condensing vaporous fluids, a condensing-chamber provided with a cooling-pipe system and means for inducing currents of air saturated with liquid 100 through such system; a supply-passage for conducting the vaporous fluid on its way to the condenser; a branch passage leading from the supply-pipe passage; a vaporizing-chamber connected with the branch passage to receive therefrom and connected with the supply-passage to discharge into the same; means for condensing vapor which has passed out from the cooling-pipe system and a drip-trap for collecting the resulting water of condensation; and an ejector operated by vaporous fluid passing through the branch pipe and arranged to take up water from the drip-trap.
36. In an apparatus for condensing or cooling fluids, a condensing or cooling chamber; a pipe system extending through the condensing or cooling chamber; means for inducing fluid through the pipe system; and a supplemental cooling device through which liquid 115 can be caused to pass directly from the condensing-chamber.
37. In an apparatus for condensing or cooling fluids, a condensing or cooling chamber; a set of pipes open at their ends and extending 125 through the condensing or cooling chamber; means for inducing currents of air through the pipes; a supplemental cooling chamber or passage about which currents of air are induced by the means employed for inducing air-currents through the pipes; connection between the supplemental cooling chamber or passage and the condensing or cooling chamber; and a spray device arranged to direct

liquid spray to points where the induced air-currents enter the pipes and passage-way about the supplemental cooling-chamber.

38. In an apparatus for condensing or cooling fluids, a condensing or cooling chamber; a supplemental cooling device Q connected with a discharge - passage leading from the condensing or cooling chamber; and a cock or valve for directing liquid flowing from the condensing or cooling chamber and directing it to the supplemental cooling device.

39. In an apparatus for condensing vaporous fluids, a condensing-chamber, and an oil-collecting device forming a passage-way for the admission of exhaust-steam and comprising a series of apertured hollow cones arranged one within another and set apart to form a set of compartments which connect by way of the apertures through the cones to provide a passage-way for the exhaust-steam, the spaces between the conical walls formed by such hollow cones being closed at their ends to cause the exhaust to circulate through said spaces and the apertures by which they are connected.

40. In an apparatus for condensing vaporous fluids, a condensing-chamber; and an oil-collecting device forming a passage-way for

the admission of exhaust-steam and comprising a shell having one end provided with an inlet-pipe, and a series of hollow cones provided with apertures and arranged within the shell, the cones being set apart to provide intervening spaces which connect by way of the apertures through the cones, and which are otherwise closed by the junction of the larger ends of the cones with the inner wall of the inclosing shell or casing.

41. An apparatus for condensing or cooling fluids, comprising a main casing, a set of pipes extending through the casing and opening at opposite sides thereof; a passage extending through the casing and also opening at opposite sides thereof; an exhaust fan or blower for inducing currents of air through both the pipes and said passage; a spray device for directing liquid spray into the air-currents entering the pipes and passage; and a supplemental cooling device arranged within the said passage and connected with the chamber in which the pipes are arranged.
